UNITED STATES PATENT OFFICE.

JAMES CROSGROVE, OF PITTSBURG, PENNSYLVANIA.

STRAIGHTENING, BENDING, AND PUNCHING MACHINE.

SPECIFICATION forming part of Letters Patent No. 296,279, dated April 1, 1884.

Application filed October 31, 1883. (No model.)

To all whom it may concern:

Be it known that I, JAMES CROSGROVE, of Pittsburgh, in the county of Allegheny and State of Pennsylvania, have invented certain new and useful Improvements in Straightening, Bending, and Punching Machines; and I do hereby declare that the following is a full, clear, and exact description of the invention, which will enable others skilled in the art to which it appertains to make and use the same, reference being had to the accompanying drawings, which form a part of this specification, in which—

Figure 1 is a side elevation of my machine, showing punch and die attachment. Fig. 2 is a plan view with bending or straightening attachment. Fig. 3 is a longitudinal vertical section of detail, showing the two-part moving head. Fig. 4 is a cross-section of same. Fig. 5 is a detail section of eccentric end of pitman. Fig. 6 is a detail view of the wedge. Fig. 7 is a plan view of central part of machine with plate V removed.

This invention relates to the construction of that general class of machines for the purpose of straightening or bending or punching bars or sheets of metal; and it consists in the peculiar form and arrangement of parts, whereby the moving head of the machine may be quickly adjusted to the varying thickness to be operated on or the degree of bend to be given the metal bars or sheets.

In the drawings, A is the bed of the machine, having the abutment or anvil B dovetailed to receive the die c, or bending or straightening block d, as shown. In the bearing E, at the rear end of frame or bed A, is journaled the main shaft F, having the usual fly-wheel and pulley at one end, and at the other the pinion G. Pinion G meshes with the spur-wheel H, whose shaft I is journaled in the pillow-blocks J, and is formed with an eccentric k, at its center, between the journals. On this eccentric k is a heavy pitman, L, which gives motion to the moving part of the press in the following manner:

The moving head is made in two separate parts, part M fitting the frame A so as to slide therein, and part N fitting and sliding

in the extension of part M. The front of 50 part M is at right angles to its length, but the rear of part N is slightly inclined, so that between the two there is a wedge-shaped space. Each of the two parts M and N is formed with the groove o in its top, near the 55 adjacent rear and front, as shown in Figs. 1 and 3, so that the grooves o converge like said faces.

A wedge-block, P, corresponding in angular disposition to the adjacent faces of parts 60 M and N, is provided with the overhanging top having the tongues or tenons q, as shown, which fit the grooves o on parts M and N. The fit is made neat, so that the faces of the block P are in intimate contact, respectively, 65 with the front and rear of parts M and N, besides having the tenons q lying in grooves o. By this construction it is obvious that a movement inwardly or outwardly (transversely) of the wedge-block P will force the head 70 N away from or draw it toward the part M in a positive manner, and in all positions interpose a solid block of metal between the two moving parts, so that the strains and shocks of operation are properly provided against. 75

A slotted lever, R, pivoted to the frame A, or to a bracket thereon, forms a convenient means of adjustment, whereby the wedge-block P may be adapted to the requirements of the material under operation while the machine is in motion. 80

The pitman L has the T-head s s, which seats in a bearing in the rear end of sliding head M, and is held there by the saddle-bars t, (see Fig. 3,) bolted to head M. 85

The double head M N is retained in position vertically by the cover-plate V, bolted to the frame A.

I claim as my invention—

1. In a straightening, bending, or punching machine, the combination, with the moving head M, of the supplementary head N, sliding therein, an interposed wedge, P, between said heads, and adapted to move transversely thereof and give them positive adjustment to and from one another, and a pivoted lever, R, connected to said wedge, substantially as described, whereby the necessary 90

95

adjustments may be readily made between the strokes.

2. The combination of head M, having top groove, *o*, and head N, having top groove, *o*,
5 the adjacent faces of one or both heads being inclined, the solid wedge-block P, having the angularly-set overhanging tenons *q*, fitting said grooves *o*, and a pivoted lever, R, substantially as described.

In testimony that I claim the foregoing as to my own I have hereto affixed my signature in presence of two witnesses.

JAMES CROSGROVE.
